CLAIM

The ornamental design for a serving cup, as shown and described.

DESCRIPTION

FIG. 1 is a front-right perspective view of a design for a serving cup, showing our new design.

FIG. 2 is a front view of the serving cup of FIG. 1.

FIG. 3 is a back view of the serving cup of FIG. 1.

FIG. 4 is a left side view of the serving cup of FIG. 1.

FIG. 5 is a right side view of the serving cup of FIG. 1.

FIG. 6 is a top view of the serving cup of FIG. 1; and,

FIG. 7 is a bottom view of the serving cup of FIG. 1.

The solid lines in FIGS. 1-7 illustrate a serving cup according to the present invention.

1 Claim, 7 Drawing Sheets
